attorney

UNITED STATES PATENT OFFICE

GEORGE E. TEMPLE, OF STONEHAM, MASSACHUSETTS

TABLE

Application filed January 6, 1930. Serial No. 418,791.

My present invention relates to tables, and more particularly to that type of table which has collapsible or folding legs or supports.

In tables of this type, considerable difficulty has been heretofore experienced in retaining or holding the legs in open position.

An important object of my present invention, therefore, resides in the provision of means to permit the ready collapsing or opening of the legs of such a table, coupled with means to positively lock said legs in their open position, thus preventing inadvertent or accidental collapsing of the table when in use.

Another object of my invention resides in the provision of means to prevent sagging of the table intermediate the supports.

A still further object of the invention resides in the fact that my novel means to prevent sagging of said table is readily adjustable, said adjustments being capable of accomplishment in a short space of time and with but little effort.

In carrying out my present invention, I preferably apply the same to tables for use at banquets or other occasions, where it is desired to collapse or fold the tables for stowage in small space after they have served their temporary use. However, it will be appreciated that my invention is equally applicable to smaller tables, such as bridge tables or in fact to any type of table, bench, support, settee, or any article of this nature adapted to be collapsed and stored away.

In practising my invention, I preferably position, on the under side of the table, intermediate the ends thereof, a pivot, preferably formed as a yoke, and preferably adjustable toward or from the bottom surface of the table. Pivoted in this yoke are a pair of toggles, one of these toggles extending toward each pair of legs, the legs being preferably arranged in pairs and each pair being manipulated as a unit. The toggles each comprise a main link flaring from the pivot point toward the legs, the first link terminating short of the legs when in open position, and a separate link being pivoted to each end of the first link, each of these second links being in turn hinged to a hinge frame on its

respective leg. On said hinged frame I provide means, cooperating with the short links above referred to, to automatically lock said legs in open position, and to prevent collapsing of the toggle links and hence of the legs until a predetermined time, preferably on reversing the position of the table to an upside-down position, when the locking means above referred to will automatically release and permit collapsing of said toggle links and hence of the legs.

Further features and objects of my invention reside in the particular details of construction thereof, and since I believe that said invention is novel, I have, therefore, claimed the same broadly in the present application.

The above and other novel features and objects of the invention, details of construction, combinations of parts and advantages, will be hereinafter more fully pointed out, described and claimed.

Referring to the drawings, illustrating a preferred embodiment of my present invention,

Fig. 1 is a side elevation, partly broken away, of my novel table;

Fig. 2 is a bottom plan view of a portion of said table;

Fig. 3 is a vertical sectional view on the line 3—3 of Fig. 1;

Fig. 4 is a cross sectional view on the line 4—4 of Fig. 2;

Fig. 5 is a fragmentary perspective view, on an enlarged scale, illustrating the preferred form of automatic locking device; and

Fig. 6 is a fragmentary perspective view, on an enlarged scale, illustrating a modification of automatic locking means.

Referring now to the drawings, for a particular description of the invention, my novel apparatus comprises a table top 1, preferably having secured to the under side thereof transverse reenforcing strips 2, 3 and 4. To the under side of the table, midway of its ends, and secured thereto or to the strip 3, if same is utilized, is a plate or flange 5, held in position by screws 6, this plate having a threaded aperture therethrough, and there being a recess 10 in the strip 3 or in the table

1 if such a strip is not utilized, the recess 10 being in alignment with the threaded aperture in the plate or flange 5. A yoke 7 has a threaded stem 8 which is threaded through 5 the aperture in the plate 5, a lock nut 9 being provided on the stem 8 to lock the yoke in the position to which it may have been adjusted.

A pivot 11 is provided through the sides 10 of the yoke 7, and pivoted on said pivot are a pair of toggles comprising a main link which consists of a pair of metallic strips 12 and 13, flaring from the pivot point, as clearly shown, and being reenforced and 15 united by transverse braces 14. A pair of legs 15 are preferably united by a brace 16, and are hinged to the strip 2 by hinges 17. Affixed to each of the legs 15 is a plate 18, preferably having a housing 19 formed thereon, and pivoted on a pivot pin 20 is a rocker arm 21, normally concealed within the housing, said housing having a cutaway portion 22, to permit digital manipulation of the rocker arm 21. As clearly illustrated in the 25 drawings, said rocker arm is over-balanced, the major portion of said arm being to one side of the pivot pin 20. Thus, when the table is in inverted position, the projecting end 23 of the arm 22, which projects through 30 the slot 24 in the plate 18, will be free of the arm 25 of the short link 26, which is pivoted at 27 to the plate 18 and at 28 to the link arms 12 and 13.

A flange 29 is provided on each of the 35 plates 18. Thus, when the legs 15 are opened, and the table is in the position illustrated in Fig. 1, the over-balanced rocker arm 21 will swing vertically and lock the arm 25 of the link 26 between the projecting end 23 of said 40 rocker arm and the flange 29, effectually preventing inadvertent collapsing of the toggle or of the legs 15. This feature is clearly illustrated in Figs. 3 and 5.

Each part 12 and 13 of the main toggle 45 link is provided at its free end with a bent corner 30, adapted to spring by the links 26 when the toggle is in extended position, to further assist in the retaining of said toggles in said extended position.

50 The threaded stem 8 may be adjusted to any desired position, to provide the greatest support, through the medium of the toggles, to the center of the table and prevent sagging thereof when under a load.

55 If desired, in place of the rocker arm 21, I may provide a plate 31 having a flange 32 thereon, and may form the arm 25 of the link 26 with a pawl 33 adapted to engage a co-operating detent in the plate 31 when the 60 toggles and links are in extended or open position, the flange 32 preventing movement of the arm 25 beyond normal open position.

65 My present novel table is economical to manufacture, simple to open or collapse, positive in its locking action, and presents a

strong, rugged, and durable structure, the advantages of which will be instantly apparent to those skilled in this art.

While I have necessarily described my present invention somewhat in detail, it will be appreciated that I may vary the size, shape and arrangement of parts within reasonably wide limits without departing from the spirit of the invention.

My invention is further described and defined in the form of claims as follows:

1. A table comprising a top, pairs of legs hinged to said top, a toggle connected to each pair of legs, a vertically adjustable pivot on said top intermediate its ends, said toggles being connected to said pivot, and means to fix said pivot in adjusted position.

2. A table comprising a top, pairs of legs hinged to said top, a toggle connected to each of said legs, a yoke attached to the under side of said top, a pivot carried by said yoke, said toggles being mounted on said pivot, means to effect movement of said yoke toward or from said top, and means to hold said yoke in fixed relation to said top at any point of adjustment.

3. A table comprising a top, a pair of legs movable as a unit hinged to said top, a toggle comprising a link pivoted at one end to said table, a pair of links pivotally attached to said first link, each of said second links being pivotally attached to one of said legs, and means on said leg automatically operable to lock said links against movement when said legs are in opened position.

4. A table comprising a top, a pair of legs movable as a unit hinged to said top, a toggle comprising a link pivoted at one end to said table, a pair of links pivotally attached to said first link, each of said second links being pivotally attached to one of said legs, and means on said leg automatically operable to lock said links against movement when said legs are in opened position, said locking means being automatically operable to unlock said links when said table is in inverted position, to permit folding of said legs.

5. In a table of the kind described, a leg, a hinged plate on said leg, a housing on said plate, an eccentrically mounted rocker arm in said housing, said housing having a slot at one end thereof, one end of said rocker arm projecting through said slot, a flange on said plate, a link pivoted to said plate, and an arm on said link adapted to be engaged by one side by said flange and on the other side by the projecting end of said rocker arm when said table is in upright position.

6. In a table of the kind described, a leg, a hinged plate on said leg, a housing on said plate, an eccentrically mounted rocker arm in said housing, said housing having a slot at one end thereof, one end of said rocker arm projecting through said slot, a flange on said plate, a link pivoted to said plate,

and an arm on said link adapted to be engaged on one side by said flange and on the other side by the projecting end of said rocker arm when said table is in upright position, said rocker arm being digitally operable to disengage said link arm.

7. In a table of the kind described, a leg, a hinged plate on said leg, a housing on said plate, an eccentrically mounted rocker arm in said housing, said housing having a slot at one end thereof, one end of said rocker arm projecting through said slot, a flange on said plate, a link pivoted to said plate, and an arm on said link adapted to be engaged on one side by said flange and on the other side by the projecting end of said rocker arm when said table is in upright position, said rocker arm being automatically operable, on inverting said table, to release said link arm.

20. In testimony whereof, I have signed my name to this specification.

GEORGE E. TEMPLE.
